UNITED STATES PATENT OFFICE.

EDSON O. SESSIONS, OF CHICAGO, ILLINOIS.

LOCKING-SWITCH.

1,286,806.

Patented Dec. 3, 1918.

Application filed June 23, 1916. Serial No. 105,346.

To all whom it may concern:

Be it known that I, EDSON O. SESSIONS, a citizen of the United States, residing at Chicago, in the county of Cook and State of Illinois, have invented a certain new and useful Improvement in Locking-Switches, of which the following is a specification.

My invention relates to an improvement in locking switches for use, particularly, with alternating currents of large volume. In connection with switches of this kind, it is necessary to lock the switches in their closed position to guard against the possibility of the switches being thrown open by the magnetic effect produced by the flow of large current through the switch blades. It frequently occurs that the amount of room available for the locking devices is limited and, since these devices must preferably be located outside of the clip jaws of the switch, it is frequently difficult to provide secure and substantial locking devices within the limited space available. By my invention, I have provided a construction by which the locking mechanism is simple, effective and durable and by which also the amount of space required to contain it is reduced to a minimum without in any way interfering with the effective operation of the locking devices. While my construction is shown herein in connection with a double-throw switch and is particularly successful for such devices, it will be understood that it may also be employed with good results in connection with single-throw switches.

A desirable embodiment of my invention is shown in the accompanying drawings, in which—

Figure 1 shows in elevation a double-throw switch complete,

Fig. 2 shows in elevation, in an enlarged view, one end of the switch blade and the clip jaws engaged thereby, the casing of the locking mechanism being cut away to show the mechanism of the locking devices,

Fig. 3 is a horizontal sectional view of the parts shown in Fig. 2 taken along the line 3—3, and

Fig. 4 is a view of the end portion to a reduced scale of an operating tool for the switch.

Similar numerals refer to similar parts throughout the several views.

As shown in Fig. 1, the switch consists of a switch blade 10, pivotally mounted at 11 to a clip block 12. Clip jaws 13 and 14 are located upon either side of the clip block 12 and in alignment therewith to be engaged by the switch blade 10 when in one or the other of its closed positions as the case may be. The clip jaws 13 and 14 carry locking catches 15 and 16 for engaging the locking hooks 17 and 18 mounted upon the movable end of the switch blade 10.

As shown more clearly in Figs. 2 and 3, the locking hooks 17 and 18 are pivotally supported upon rods 19 and 20 extending between the side walls of the lock casing 21 and these hooks are provided within the casing with ears 22 and 23 provided with cutwardly opening slots 24 and 25 to receive the pins 26 and 27 carried by the slotted ends of the levers 28 and 29. The ears 22 and 23 are of a thickness to enter freely into the slots in the ends of the levers 28 and 29. These levers are pivotally supported upon rods 30 and 31 extending between the side walls of the casing 21 and the lever 29 is provided with an upwardly extending ear 32 having an outwardly opening slot 33 for engaging a pin 34 carried by the ear 35 extending downwardly from the lever 28. The ear 32 is of a thickness to enter freely into the slot formed in the ear 35. The lefthand end of the levers 28 and 29 are extended beyond the openings 36 formed through the side walls of the casing 21 and overlap said openings when the hooks 17 and 18 are in their locking position. A guard wall 37 extends between the side walls of the casing 21 at the inner edges of the openings 36 and between this guard wall and the ears 32 and 35 a helical spring 38 is disposed with its ends in engagement with pins 39 and 40 carried by the levers 28 and 29 respectively. The relation of the lever arms to the various parts is such that a minimum permissible amount of motion of the operating end of either of the levers 28 or 29 by means of an operating tool such as shown at 41 in Fig. 4, inserted through the openings 36, produces a sufficient amount

of motion of the locking hooks 17 and 18 to positively disengage them and at the same time permit these hooks to be of such substantial construction as to perform their intended function of positively holding the switch in its closed position in engagement either with the clip 13 or 14 as the case may be. Furthermore, it will be observed that the operation of either of the levers 28 or 29 by means of the operating tool operates the other of said levers and that, therefore, for any operation of the locking mechanism by means of the operating tool both of the locking hooks are withdrawn from their engaging position. A further result secured by the arrangement of parts described is that, when the operating tool 41 moves the switch to either of its closed positions it presses against one of the levers which moves both of the locking hooks to their releasing position, as a result of which the switch is closed without engagement of the hooks with the locking catches, and thus wear of the parts is eliminated. If for any reason the frictional engagement between the clip jaws and the switch blade is insufficient to cause such pressure by the tool 41 on the arm 28 or 29 as to cause a lengthening of the spring 38 during the closing operation, the inclined surfaces of the hooks 17 and 18 and locking catches 15 and 16 positively move the locking hooks outwardly against the action of the spring 38 so that proper engagement may be had between the locking hooks and the locking catches. The same is true if for any reason the switch is moved into its closed position by a force applied to the outside of the lock casing or directly to the switch blade.

40 While the lock casing is shown as attached to the end of the switch blade by means of rivets, it will be understood that this construction does not need to be followed but that on the other hand equivalents thereof may be employed without departing from my invention. And furthermore I do not limit myself to the exact mechanical construction shown in carrying out my invention, but on the other hand may employ known mechanical equivalents thereof.

What I claim is:

1. In a locking switch, the combination of a switch blade, a clip block pivotally supporting said switch blade, clip jaws for engaging said blade in its closed position, a locking catch carried by said clip jaws, a casing extending from the free end of said switch blade, a locking hook pivotally supported in said casing at a distance from the blade pivot to engage said catch when the switch is closed, a lever pivotally mounted in said casing and overlapping openings formed through the walls of said casing to receive an operating tool, a spring for hold-

ing said lever in its overlapping position, and mechanism connecting said lever and said hook to impart to said hook a greater angular motion than that of said lever when the latter is operated, said mechanism consisting of a second lever also overlapping said openings whereby motion of the operating tool in either direction in said openings operates one or the other of said levers as the case may be and thereby moves said hook to its releasing position.

2. In a locking switch, the combination of a switch blade, a clip block pivotally supporting said switch blade, clip jaws for engaging said blade in its closed position, a locking catch carried by said clip jaws, a casing extending from the free end of said switch blade, a locking hook pivotally supported in said casing at a distance from the blade pivot to engage said catch when the switch is closed, a lever pivotally mounted in said casing and overlapping openings formed through the walls of said casing to receive an operating tool, a spring for holding said lever in its overlapping position, and mechanism connecting said lever and said hook to impart to said hook a greater angular motion than that of said lever when the latter is operated, said mechanism consisting of a second lever also overlapping said openings whereby motion of the operating tool in either direction in said openings operates one or the other of said levers as the case may be and thereby moves said hook to its releasing position, and a second locking hook engaged by said second lever and extending in opposite direction to the first named locking hook and pivotally supported in said casing, clip jaws for engaging said switch blade when in a second operative position, and a locking catch carried by said last named clip jaws for engaging said second locking hook, whereby operation of either of said operating levers serve to move both locking hooks to their releasing position.

3. In a locking switch, the combination of a pivotally mounted switch blade, clip jaws for engaging said switch blade in its closed position, a locking catch associated with said clip jaws, a casing carried by the free end of said switch blade, a locking hook pivotally supported in said casing and projecting from one edge thereof, multiplying levers mounted in said casing and engaging said locking hook, one of said levers overlapping openings through the side walls of said casing to receive an operating tool whereby operation of said overlapping lever imparts to said locking hook greater angular motion than that of said overlapping lever, and a second locking hook extending from the opposite edge of said casing and engaged by said multiplying levers, second clip jaws for engaging said switch blade in another op-

erative position and a locking catch associated with said second clip jaws for engaging said second locking hook.

4. In a locking switch, the combination of 5 a pivotally mounted switch blade having two operative positions, clip jaws for engagement with said blade in each operative position, a locking catch associated with each of the clip jaws, a casing carried by the free 10 end of the switch blade, a locking hook pivotally supported in said casing and extending therefrom to engage each locking catch, an operating lever in the casing engaging each locking hook for imparting greater angular 15 motion thereto than the angular motion of the operating lever, each operating lever overlapping openings formed through the side walls of said casing to receive an operating tool, and a connection between said operating 20 levers whereby the operation of one of said levers operates the other of said levers.

5. In a locking switch, the combination of 25 a pivotally mounted switch blade having two operative positions, clip jaws for engagement with said blade in each operative position, a locking catch associated with each of the clip jaws, a casing carried by the free 30 end of the switch blade, a locking hook pivotally supported in said casing and extending therefrom to engage each locking catch, an operating lever in the casing engaging each locking hook for imparting greater angular motion thereto than the angular motion of the operating lever, each operating lever overlapping openings formed through the side walls of said casing to receive an operating tool, a connection between said operating levers whereby the operation of one of said levers operates the other of said levers, and a helical spring 35 secured at its ends to said operating levers to hold them in their overlapping position.

6. In a locking switch, the combination of 40 a switch blade, a clip block pivotally supporting said switch blade, clip jaws for engaging said blade in its closed position, a locking catch carried by said clip jaws, a casing extending from the free end of said switch blade, a locking hook pivotally supported in said casing at a distance from the blade pivot to engage said catch when the switch is closed, a lever pivotally mounted in said casing and overlapping openings formed through the walls of said casing to receive an operating tool, a spring for holding said lever in its overlapping position, and mechanism connecting said lever and said hook, said mechanism consisting of a second lever also overlapping said openings, 45 whereby motion of the operating tool in either direction in said openings operates one or the other of said levers as the case may be and thereby moves said hook to its releasing position.

7. In a locking switch, the combination of 65 a pivotally mounted switch blade, clip jaws for engaging said switch blade in its closed position, a locking catch associated with said clip jaws, a casing carried by the free end of said switch blade, a locking hook pivotally supported in said casing and projecting from one edge thereof, levers mounted in said casing and engaging said locking hook, one of said levers overlapping openings through the side walls of said casing to 70 receive an operating tool whereby operation of said overlapping lever imparts to said locking hook greater angular motion than that of said overlapping lever, and a second locking hook extending from the opposite 75 edge of said casing and engaged by said levers, second clip jaws for engaging said switch blade in another operative position and a locking catch associated with said second clip jaws for engaging said second 80 locking hook, said levers engaging each other and also connected with said locking 85 hooks whereby operation of said overlapping lever imparts to said locking hook greater angular motion than that of said overlapping lever.

8. In a locking switch, the combination of 90 a pivotally mounted switch blade having two operative positions, clip jaws for engagement with said blade in each operative 95 position, a locking catch associated with each of the clip jaws, a casing carried by the free end of the switch blade, a locking hook pivotally supported in said casing and extending therefrom to engage each locking 100 catch, an operating lever in the casing engaging each locking hook, each operating lever overlapping openings formed through the side walls of said casing to receive an operating tool, and a connection between 105 said operating levers whereby the operation of one of said levers operates the other of said levers.

9. In a locking switch, the combination of 110 a pivotally mounted switch blade having two operative positions, clip jaws for engagement with said blade in each operative position, a locking catch associated with each of the clip jaws, a casing carried by the free end of the switch blade, a locking hook 115 pivotally supported in said casing and extending therefrom to engage each locking catch, an operating lever in the casing engaging each locking hook, each operating lever overlapping openings formed through the side walls of said casing to receive an operating tool, a connection between said operating levers whereby the operation of one of said levers operates the other of said levers, and a helical spring secured at its 120 ends to said operating levers to hold them in their overlapping position.

10. In a locking switch, the combination

of a pivotally mounted switch blade having two operative positions, clip jaws for engagement with said blade in each operative position, a locking catch associated with each of the clip jaws, a casing carried by the free end of the switch blade, a locking hook pivotally supported in said casing and extending therefrom to engage each

locking catch, and two operating levers mounted in said casing and engaging said locking hooks, the operation of each of said levers serving to move both of said catches to their releasing position. 10

In witness whereof, I hereunto subscribe my name this 19th day of May A. D. 1916. 15

EDSON O. SESSIONS.
